Specification for Design.

Patented July 12, 1910.

Application filed May 16, 1910. Serial No. 561,785. Term of patent 3½ years.

To all whom it may concern:

Be it known that I, ADOLPH PETZOLD, a citizen of the United States, residing in the city of Philadelphia, State of Pennsylvania, have invented a certain new, original, and ornamental Design for a Rug, of which the following is a specification, reference being had to the accompanying drawing forming part thereof.

The figure is a plan view of a quarter section of a rug, the other three quarters being identical therewith, showing my new design.

I claim:

The ornamental design for a rug, as shown.

ADOLPH PETZOLD.
